United States Patent

Des. 236,316
Patented Aug. 19, 1975

236,316

OVEN

Donald J. Booty, Frankfort, Ill., and Irving R. Belinkoff,
Queens Village, and David W. Balter, Bronx, N.Y.,
assignors to LCA Corporation, Yonkers, N.Y.

Filed Aug. 24, 1973, Ser. No. 378,857

Term of patent 14 years

Int. Cl. D7—02
U.S. Cl. D7—126

FIG. 1

FIG. 4

FIG. 2

FIG. 3

FIG. 5

FIG. 6

FIG. 1 is a front perspective view of an oven in accordance with the present invention;

FIG. 2 is a front elevation view thereof;

FIG. 3 is a rear elevation view thereof;

FIG. 4 is a right side view thereof;

FIG. 5 is a top plan view thereof;

FIG. 6 is a bottom plan view thereof.

The left side elevation view is a mirror image of the right side elevation view.

We claim:

The ornamental design for an oven, substantially as shown and described.
